UNITED STATES PATENT OFFICE.

MAX MITTENDORFF, OF NEW YORK, N. Y., ASSIGNOR TO SUTRO BROTHERS BRAID COMPANY, OF NEW YORK, N. Y., A CORPORATION OF NEW YORK.

DESIGN FOR BRAID.

SPECIFICATION forming part of Design No. 36,079, dated September 16, 1902.

Application filed July 31, 1902. Serial No. 117,902. Term of patent 14 years.

To all whom it may concern:

Be it known that I, MAX MITTENDORFF, a citizen of the United States, residing at Manhattan borough, New York city, in the county of New York and State of New York, have invented and produced a new, original, and ornamental Design for Braid, of which the following is a specification.

My invention relates to a new and original design for braid, and is illustrated in the accompanying drawing as showing a face view of the braid.

The leading feature of my design resides in an imperforate braid having bows placed longitudinally to and at intervals along a face of the braid. The bows are narrower than the braid and placed at the median line thereof, so that the braid projects symmetrically each side of or beyond the bows.

As seen in the annexed drawing, the design

consists in the braid *a*, having bows *b*. The bows are placed longitudinally to the braid, the loop parts of each bow being made to extend in the direction of the length of the braid. The bows are placed at intervals required to secure a desired effect.

My design presents a braid having bow-shaped ornaments, and it has a novel, pleasing, and distinguished appearance.

What I claim as new, and desire to secure by Letters Patent, is—

The ornamental design for a braid, substantially as herein shown and described.

In testimony whereof I have hereunto set my hand in the presence of two subscribing witnesses.

MAX MITTENDORFF.
